(57) **CLAIM**

The ornamental design for an electric fan, as shown and described.

DESCRIPTION

FIG. 1 is a front elevational view of an electric fan showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in FIGS. 1, 2, 5, 6 and 7 depict parts of the electric fan that form no part of the claimed design.

1 Claim, 4 Drawing Sheets(56)
